UNITED STATES PATENT OFFICE
2,585,560
METAL SPRAYING GUN

Joel Abdon Albin Larsson, Uppsala, Sweden, assignor to Hjalmar Andren & Soner, Stockholm, Sweden

Application March 10, 1950, Serial No. 148,818
In Sweden March 14, 1949

1 Claim. (Cl. 118—302)

1

This invention relates to an apparatus for spraying metals, such as tin, lead or the like in finely divided state onto surfaces, to be metalized.

Apparatus for this purpose are known, which however are subject to repeated interruptions in operation.

The purpose of the present invention is to obtain a metal spraying apparatus or metal spraying gun, in which the discrepancies of previously known apparatus are eliminated.

An embodiment of the invention is shown in the accompanying drawing.

Fig. 1 is a rear view of a metal spraying gun according to the invention.

Fig. 2 is a sectional side-view of the gun shown in Fig. 1.

The apparatus shown comprises a casing 1, the lower part of which is shaped in form of a handle 2. The casing 1 encloses a horizontal air channel 3 opening at the rear of the casing. Said air channel communicates within the casing with a vertical air channel 4 leading to the upper part of the casing. The horizontal air channel 3 contains a spring actioned ball valve 5, which is operable by a bar 6 slidably guided in the forward part of the casing 1. The vertical air channel 4 is at its upper end by means of a pipe connecting nut 7 connected to an air tube 14. The rear end of the horizontal air channel 3 is provided with connecting means 8 for an air supplying hose (not shown). The rear of the casing 1 is also provided with connecting means for an electric feed leader 9, leading to electric connecting means within the casing. The upper part of the metal spraying gun comprises a cylindrical metal container 10, the forward end of which is formed into a valve casing 11. It will be noted also from the drawing that the longitudinal axis of container 10 occupies a horizontal position when case 1 is held in an upright position. The forward portion of the container 10 is surrounded by an electric heating element 12. At the upper side of the container there is a filling device 13. The air tube 14, connected to the upper end of the vertical air channel 4, is wound around the heating element 12 in form of a solenoid. Said air tube ends into a nozzle 15 immediately adjacent to the under side of the valve casing 11. The under side of the tube solenoid 14 is covered by a protecting plate 16 (Fig. 1). Between the upper part of the casing and the protecting plate 16 are disposed a number of heat deflecting plates 17 adapted to prevent the transmission of heat

2 to the handle 2. The actioning means of the metal spraying gun comprise a trigger 18 pivotally mounted on a pin 19. The upper end of the trigger is pivotally connected to one end of a link 20, the other end of which is connected to an angle lever 21. This angle lever is on the other side connected to an actuating bar 22, the upper end of which has a holder 23 for a valve needle 24 fixedly mounted thereon. The wall between the container 10 and the valve housing 11 is traversed by a channel 25. In order to prevent liquid metal to flow back from the valve housing into the container when the metal spraying gun is turned upwardly, said channel 25 runs obliquely upwards towards the valve casing.

The metal spraying gun described above works in the following manner:

The metal to be sprayed is filled into the container 10 and is kept in liquid state in the container and the valve casing 11 by means of the heating element 12. The horizontal air channel 3 is by means of a hose connected to a source of compressed air. When pressing in the trigger 18, the valve needle 24 in the valve casing 11 is displaced upwards and opens the outlet of the valve casing. Simultaneously the bar 6 is displaced backwards and opens the ball valve 5, thus admitting compressed air into the vertical channel 4 and therefrom to the solenoid-shaped tube 14, where the compressed air is heated. The compressed air thus heated passes through the nozzle 15 and finely divides the metal flowing out through the opening at the lower end of the valve casing 11. The heating of the air prevents the cooling of the outlet from the valve casing 11 and of the metal during the spraying.

What I claim is:

A metal spraying gun comprising in combination a casing having a lower handle portion by 40 which to hold the same in an upright position, an air inlet channel within said casing, a valve in said channel controlling flow of air therethrough, a container for the metal disposed transversely atop said casing such that the longitudinal axis of said container occupies a horizontal position when said casing is held in an upright position, means establishing in the forward end wall of said container a smaller valve chamber the axis of which is disposed vertically when said casing is held in its upright position, said valve chamber being in heat conducting relation with said container and communicating with the latter by means of a channel extending obliquely downward from the valve chamber to the interior of

the container, a downwardly directed nozzle at the lower end of said valve chamber for discharging molten metal, a valve needle displaceable longitudinally within said valve chamber for controlling discharge of molten metal through said nozzle, an electrical heating element and a spiral air heater tube surrounding said container, one end of said tube being connected to said air inlet channel and the other end terminating in a nozzle opening immediately below and at the side 10 of the outlet of said nozzle for discharge of molten metal, a trigger pivotally mounted upon said casting, air valve actuating means extending between said air valve and trigger, and a lever mechanism extending between said trigger and the upper 15 end of said valve needle, said lever mechanism extending along the outside of said container and joining said valve needle outside of said valve chamber whereby to effect simultaneously dis-

charge of molten metal from said valve chamber and heated air from said air tube upon actuation of said trigger.
